[57] CLAIM

The ornamental design for a watch support, as shown and described.

DESCRIPTION

FIG. 1 is a top plan view of a watch support showing our new design;

FIG. 2 is a bottom plan view thereof;

FIG. 3 is a right side elevational view thereof;

FIG. 4 is a left side elevational view thereof;

FIG. 5 is a front elevational view thereof, the rear elevational view being a mirror image thereof; and
FIG. 6 is an exploded top and right front perspective view thereof.
